(57) **CLAIM**

The ornamental design for a tire for motorcycle, as shown and described.

DESCRIPTION

FIG. 1 is a front perspective view of a tire for motorcycle showing my new design;

FIG. 2 is a front view thereof;

FIG. 3 is a left side view thereof;

FIG. 4 is a rear view thereof;

FIG. 5 is a right side view thereof;

FIG. 6 is a bottom view thereof;

FIG. 7 is a top view thereof; and,

FIG. 8 is a partial enlarged view of the portion 8-8 in FIG. 2.

The broken lines in the drawings used for demarcation of enlarged portions of the tire for motorcycle form no part of the claimed design.
